(57) **CLAIM**

We claim the ornamental design for a bottle, as shown and described.

DESCRIPTION

FIG. 1 is a side elevation view of a bottle showing the present invention, the opposite side being a mirror image thereof;

FIG. 2 is a top plan view thereof; and,

FIG. 3 is a perspective view thereof, shown at an enlarged scale.

The broken lines shown in the drawings are for illustrative purposes only and form no part of the claimed design.
